US0D1069616S

(12) **United States Design Patent** (10) **Patent No.:** **US D1,069,616 S**
(45) **Date of Patent:** **** Apr. 8, 2025**

(54) **TRACKER HOUSING**

(71) Applicant: **MOTHERBEAR, INC.**, Maple Grove, MN (US)

(72) Inventors: **Demetrious T. Kutzke**, Maple Grove, MN (US); **Patrick McArdle**, Boulder, CO (US)

(73) Assignee: **MOTHERBEAR, INC.**, Maple Grove, MN (US)

(**) Term: **15 Years**

(21) Appl. No.: **29/916,496**

(22) Filed: **Nov. 13, 2023**

(51) **LOC (15) Cl.** **10-04**

(52) **U.S. Cl.**

USPC **D10/74**; D10/70; D10/104.1

(57) **CLAIM**

The ornamental design for a tracker housing, as shown and described.

DESCRIPTION

FIG. 1 is a perspective view of the tracker housing;

FIG. 2 is a front view of the tracker housing;

FIG. 3 is a rear view of the tracker housing;

FIG. 4 is a left view of the tracker housing;

FIG. 5 is a right view of the tracker housing;

FIG. 6 is a top view of the tracker housing; and,

FIG. 7 is a bottom view of the tracker housing.

The portions of the rear of the tracker housing shown in broken lines in FIG. 3 form no part of the claimed design.

1 Claim, 5 Drawing Sheets
